UNITED STATES PATENT OFFICE.

CHARLES H. GOULD, OF NEW YORK, N. Y.

STEP OR STAIR.

SPECIFICATION forming part of Letters Patent No. 251,713, dated January 3, 1882.

Application filed May 5, 1879.

To all whom it may concern:

Be it known that I, CHARLES H. GOULD, of the city, county, and State of New York, have invented Improvements in Steps or Stairs; 5 and I do hereby declare that the following is a full and exact description thereof, reference being had to the accompanying drawings, making part of this specification—

Figure 1 being a top view of a step or stair 10 provided with my improvements; Fig. 2, a front view of the same; Fig. 3, a transverse vertical section thereof; Fig. 4, a section like Fig. 3, showing a modified construction of the nosing-shield.

Like letters designate corresponding parts 15 in all of the figures.

My invention consists in an improved india-rubber or elastic covering for a step or stair, used especially as a safety-step for outdoor use, 20 and in a nosing-shield to protect both the edge of the elastic covering and the nosing of the step or stair.

For my improved elastic covering to steps and stairs to prevent slipping on and wear of the step, first, I make a body, A, of thick firm canvas or equivalent fibrous base, and cover it with a thickness of vulcanized india-rubber, 25 a. The canvas gives body and firmness to the covering, enabling it to retain its form and position and to be secured to the step or stair by simple screws, bolts, or nails.

As a further improvement in the step-covering I combine alternate strips A A of the canvas and india-rubber or other soft or elastic material, however made, and intermediate narrow strips, B B, of iron, wood, or other suitable hard material. These alternate strips of elastic and hard materials serve two important purposes. First, the hard strips serve to keep 30 the soft or elastic strips in place and prevent the abrasion or fretting of their edges; second, it allows any one or more strips to be removed and replaced when worn away without removing the others on the step, it being shown by 35 experience that some parts of the covering,

particularly the front part, will wear away much faster and sooner than the rest. Thus I save the renewal of any part of the covering till it is worn out, rendering the use of the covering more economical than if made of one 50 piece. The india-rubber or elastic strips may be somewhat thicker than the hard intermediate strips to receive the first wear. The outer strips may be of the hard material; but for the protection of the edge of the front strip, which 55 I prefer to be of the soft or elastic material, I employ the nosing-shield C, which forms another feature of my invention. This nosing-shield consists of a strip of iron, brass, or other suitable metal or material, fitting over the nosing or front edge of the stair or step, either over the upper part thereof only, as shown in Figs. 2 and 3, or over the whole width of the nosing, as shown in Fig. 4; and it also projects above the nosing, so as to abut against 60 and protect the front edge of the elastic covering of the step or stair. This nosing-shield is formed of good shape for proper appearance and proper to fit upon the step or stair nosing. It is attached to the step or stair by screws or 65 other suitable means. Not only does this nosing-shield protect the edge of the elastic covering from wear and fretting, but also the edge of the step or stair itself; and it may be used on stairs and steps when no elastic covering is 70 employed thereon.

What I claim as my invention, and desire to secure by Letters Patent, is—

The combination of a step or stair, D, mat or soft covering A, and nosing-shield C, arranged to project above the stair-nosing to protect the mat, substantially as and for the purpose herein specified.

The foregoing specification signed by me this 27th day of November, 1878.

CHARLES H. GOULD.
